TIME-SETTING DEVICE FOR FUSES

Adolf Weisz, Budapest, Hungary; vested in the
Alien Property Custodian

Application October 25, 1941, Serial No. 416,465
In Hungary July 1, 1941

7 Claims. (Cl. 161—1)

This invention relates to such type of time-setting devices for fuses in which two members cooperate to initiate a movement resulting in firing the fuse, one of said members, which is rotated by a clockwork, being so set in relation to the other, which is secured against rotation, that a predetermined time depending on the position to which the rotatable member is set, will elapse before a relative position is reached in which one of the members is allowed to initiate, under the action of a spring, the movement resulting in firing the fuse.

The principal object of the invention is to simplify the construction of the time setting device so that the component parts may be of simple form and reduced in number and that the usual inexpensive methods of manufacture in large numbers may be employed without prejudice to reliability and accuracy in function. Another object of the invention is to provide such a safety against untimely firing during the setting operation and within a predetermined but variable time after the clockwork was set going as will prevail even against wrong manipulation.

With the foregoing objects in view, together with such other objects and advantages as may subsequently appear, the invention resides in the parts and features, and in the combination, construction and arrangements of parts hereinafter described and claimed and illustrated by way of example in the accompanying drawing, in which:

Fig. 1 is a side view, partly in section, of an embodiment of my time-setting device constructed to allow time-setting for a number of days, if desired, the wheels of the well-known clock-work train being, for the most part, omitted for the sake of clearness of illustration.

Fig. 2 is a diagrammatical top view of the same device.

Fig. 3 is a cross section taken on the line 3—3 of Fig. 1 as seen from below.

Fig. 4 is a diagrammatic cross section taken on the line 4—4 of Fig. 1 as seen from above.

Figs. 5 and 5^a are diagrammatic illustrations of details in connection with the toothed wheel 29.

Three circular plates 7, 8, 9 supported by three pillars 6 constitute the framework of the device. The mainspring 10 of the clockwork generally designated by C is secured with its outer end to one of the pillars 6 and its inner end is connected to the mainspring shaft 12 which has a quadrangular extremity 11 to receive a key for winding up the clockwork. Only the toothed wheel 13 carried by the shaft 12 and the escapement-wheel 14 are shown as parts of the well-known clockwork 55

train; the intermediate wheels as well as the balance, all arranged like the escapement-wheel 14 between two additional circular plates 15 and 16 supported on small studs, not shown, above plate 8 of the framework, are omitted for the sake of clearness.

A pinion 17 secured to the lower end of the mainspring shaft 12 meshes with a wheel 19 which when rotated by the clockwork carries with itself the member to be set according to the time appointed for firing the fuse. This setting member consists, in the construction as illustrated, of a hollow cylinder 18 able to rotate but unable of axial movement and having a longitudinal slot 20. A springy arm 21 is so mounted upon the framework plate 9 radially of the cylinder 18 as to press against the annular bottom surface of the latter. The inner end of this arm 21 is connected with a bolt 22 which may axially move in an opening of plate 9 and will, under the combined action of the springy arm 21 and a helical spring 24 wound upon its shaft portion, penetrate into the hollow space within the cylinder 18 as soon as the latter takes an angular position in which the slot 20 coincides with the arm 21. The upper end of the cylinder extends to form a disk 25 in contact with the lower face of toothed wheel 19. A shaft 26 rigidly connected with the cylinder 18 penetrates the hollow shaft 27 of wheel 19 and carries, above the uppermost framework plate 7 and in the same angular position as that of the slot 20, a pointer 28 which thus indicates at all times the momentary angular position of the slot on a dial provided on the upper surface of plate 7.

In order to bring the slot 20 into a desired position corresponding to the time appointed for firing the fuse, the pointer 28 could be turned or set directly by hand. However, in the embodiment of the time-setting device as illustrated by way of example, the pointer 28 is connected by a train of transmission wheels 29, 30, 31, 32 to a longer pointer 33 whereby more exact setting and reading of the angular positions of slot 20 is obtained. Toothed wheel 29 is rigidly connected, like pointer 28, to shaft 26, whereas the pinwheel 32 rotates together with the pointer 33 loosely on the same shaft. To obtain correct meshing without idle play between the pins of wheel 33 and the teeth of wheel 29 when the latter are not fashioned with precision, a duplicate of wheel 29, designated by 29', is loosely mounted on shaft 26 above and in proximity to wheel 29 as shown in Fig. 1, and an excentrical point of wheel 29 is connected with an excentrical point of wheel 29' by a spring 42, Fig. 5, which tends to bring these two points

nearer to, or if desired farther from, each other and thereby to turn the loosely mounted wheel 29' about the shaft 26 which is rigidly connected with wheel 29. Of course, the pins of pinwheel 30 in mesh with the double wheel will not allow an angular movement between the individual wheels 29 and 29' greater than determined by the fact that the pins of wheel 30 are embraced on both sides without play by the teeth of the double wheel 29, 29' as shown in Fig. 5a.

As shown in Figures 1 and 4, near by and above the escapement-wheel 14, a two-armed lever 34 is so mounted upon a pivot 35 secured on plate 15 that it may be rocked between two stops 37, 38, and in its position shown in Fig. 4, a nose 36 15 downwardly projecting therefrom through an opening 39 in plate 15 engages the teeth of the escapement-wheel 14 so as to check the rotation of the latter and thereby stop the clockwork till the lever 34 is swung in the direction of the arrow 20 shown in Fig. 4 to set free the escapement-wheel.

The clockwork C as illustrated by way of example is so designed that when it is set going, the longer pointer 33 performs one complete rotation in twelve hours. The numbers "1" to "12" 25 shown on the outer scale 33' of the dial-plate to be seen in Fig. 2 indicate therefore the positions occupied in turn by the longer pointer 33 from hour to hour while the clockwork is going. The transmission ratio between the longer pointer 33 and the shorter one 28 is so calculated that during a complete rotation of the longer pointer, the shorter one steps forward by one graduation only on the inner scale 28' so that each graduation on the inner scale corresponds to a duration of twelve hours, but in Fig. 2 every second graduation only is marked by a number. On the inner scale, the graduation marked "0" coincides with the bisecting line of the radial arm 21, and the shorter pointer indicates the momentary angular distance of the slot 20 from arm 21. With a view to allow the pointers to be set by hand in the usual "clockwise" direction in accordance with the time appointed, the clockwork is so designed as to rotate the pointers in the direction opposite to the usual "clockwise" direction. Thus, when the longer pointer 33 is rotated by hand till the shorter pointer reaches e. g. the graduation marked "72" and the clockwork is wound up and set going by throwing the lever 34 out of engagement with the escapement-wheel 14, the clockwork will have to go on during seventy-two hours to carry the pointer 28 back to the position marked "0" so that the angular position of slot 20 being always identical with that of pointer 28, seventy-two hours must pass away till the slot 20 will so coincide with the radial arm 21 as to allow the latter to snap into the slot.

A positive driving connection being provided between the pointers and the cylinder 18, the cylinder slot 20 will exactly follow the rotation of the shorter pointer 28, when the pointers are turned to be set for the time appointed. At the same time, the frictional coupling between cylinder 18 and toothed wheel 19 will allow the cylinder to be rotated without imparting rotation to wheel 19 and to the train of wheels in connection with the latter. On the contrary, when the clockwork is going and the wheel 19 is driven by the mainspring shaft 12 through pinion 17, the frictional coupling between wheel 19 and disk 25, which latter is pressed against wheel 19 under the combined action of the springy arm 21 and of the helical spring 24, will cause the cylinder 18 to be carried by the rotating wheel 19, and

the pointer 28 rotating together with the cylinder transmits the rotation through the train of wheels 29 to 32 also to the pointer 33 so that both pointers wander back with the course of time, and from their position one can read at any moment the time which has still to pass till the shorter pointer 28 will reach the position marked "0" and the arm 21 can snap into the slot 20 so as to allow the bolt 22 to penetrate 10 into the cavity of cylinder 18 which movement results in firing the fuse.

With a view of providing safety against an untimely release of bolt 22 by an accident such as voluntary wrong or improper manipulation of the pointers, precautionary measures have been taken to the effect that if the spring 10 has been fully wound a predetermined amount of time will have to pass before bolt 22 can be released. For this purpose, the disc 25 which is integral with cylinder 18 has a peripheral nose 39 (see Fig. 3) and wheel 19 has a pair of downwardly projecting stops 40 and 41 which are positioned to be engaged by nose 39. In each case, when the device is to be placed in operation, spring 10 is fully wound and this operation turns wheel 19 so that the stops 40 and 41 are positioned as shown. When in this position, as cylinder 18 is rotated toward the position where release of bolt 22 takes place, nose 39 is engaged by either stop 40 or stop 41. Thus, for example, in Fig. 3, if pointer 28 is turned clockwise from the broken-line position, nose 39 will engage stop 40 before slot 20 comes into alignment with spring arm 21 to release bolt 22. In this embodiment, nose 39 is not in alignment with pointer 28, there being an angle β between the nose and the pointer. It will be seen from Fig. 3 that the angular distance α between stop 40 and the bisecting line of the radial arm 21, which coincides with the graduation marked "0" of scale 28', is greater than the unvariable angular distance β between the nose 39 and the slot 20 which latter coincides with pointer 28. If therefore one would try to bring the pointer 28 to the position marked "0" 45 by turning the pointer 33 by hand in the direction of the arrow shown in full lines in Fig. 2—this same direction appearing in Fig. 3, which represents a view as seen from below, in the opposite sense as shown in dotted lines—the nose 39 will strike against stop 40 and thus prohibit the pointer 28 from approaching the position marked "0" to an angular distance less than $\alpha - \beta$. The stop 40 while being rotated by the clockwork, has to perform an advance corresponding to an angle $\alpha - \beta$ in its travel towards the graduation marked "0" i. e. a time corresponding to an angle $\alpha - \beta$ has to pass away to enable the pointer 28 to be brought into the position marked "0."

In case the value of angle β is reduced to zero, i. e., the nose 39 and the slot 20 are disposed in the same radial plane, the angular distance α of stop 40 from the graduation marked "0" will determine in itself the minimum of time the clockwork has to go before release of bolt 22 can anyhow take place.

When the clockwork is entirely wound up, the stop 40 will take a position at a definite angular distance from the fixed mark "0" so that in a clockwork assembled and entirely wound up, the angle α has a definite value, and the angle β being invariable, also the angle $\alpha - \beta$ has a definite value. Thus, for every setting device completely assembled and with its clockwork completely wound up, there is a predetermined time which must pass away after the clockwork has been

set going, and which is independent of the time of firing determined by the occasional position of the setting member, before release of the member serving to initiate the firing can anyhow take place. However, every mechanician acquainted with the construction described may vary the value of angle α , and thereby increase or decrease at will the duration of security, by removing the pinion 17 and giving the wheel 19 a partial turn proportionate to the change desired before putting the pinion back in its place.

With a view to prohibit the pointer 28 from reaching untimely the graduation marked "0" also when turned by inadvertence in the direction opposed to the arrow shown in dotted lines in Fig. 3 i. e. in the direction in which the numbers progress on scale 28', a second stop 41 may be provided on wheel 19 in such an angular position as to allow the pointer 28 to be set also for the longest time i. e. for one hundred and ninety-two hours in the example illustrated.

What I claim is:

1. A time-setting device for fuses, comprising a clockwork in combination with a setting member rotatably mounted and cooperating with a member having a fixed angular position in relation thereto to initiate a movement resulting in firing the fuse; a disk in positive driving connection with said clockwork and in frictional driving connection with said setting member, a hollow shaft upon which said disk is mounted, and a shaft located in said hollow shaft and providing a mounting for said setting member; springy means tending to induce one of said cooperating members to initiate the movement which results in firing the fuse and becoming operative in a predetermined angular position of said setting member in relation to the member having a fixed angular position; and means indicating the momentary angular position of said setting member.

2. A time-setting device for fuses comprising, a clockwork in combination with a setting member which is in the form of a hollow cylinder having a longitudinal slot therein and rotatably mounted; a springy arm cooperating with said slot and extending radially with respect to said hollow cylinder and tending to penetrate said slot, said springy arm having a fixed angular position in relation to said hollow cylinder and the movement of said springy arm being to effect the firing of the fuse; a disk in positive driving connection with said clockwork and in frictional driving connection with said setting member; springy means tending to induce one of said cooperating members to initiate the movement which results in firing the fuse and becoming operative in a predetermined angular position of said hollow cylinder in relation to said springy arm; and means indicating the momentary angular position of said setting member.

3. A time-setting device for fuses, comprising

a clockwork in combination with a setting member rotatably mounted; a member cooperating with said setting member and having a fixed angular position in relation thereto to initiate a movement resulting in firing the fuse; a disc in positive driving connection with said clockwork and in frictional driving connection with said setting member; springy means tending to induce one of said cooperating members to initiate the movement which results in firing the fuse and becoming operative in a predetermined angular position of said setting member in relation to the member having a fixed angular position; and means indicating the momentary angular position of said setting member, said setting member having a projecting nose and said disc having a stop cooperating with said nose to prevent the setting member from taking the angular position in which the springy means becomes operative, said stop being effective for a predetermined duration of time after said clockwork has been fully wound and placed into operation.

4. In a time-setting device for fuses, a clockwork having a predetermined initial position stop means carried by said clockwork and adapted to be in a predetermined initial position which is attained when said clockwork is fully wound, fuse-firing means has a frictional driving connection with said clockwork and including setting means to set the time of the firing of the fuse, and means carried by said setting means to cooperate with said stop means and preventing the firing of the fuse during a period of time after said clockwork has been started from said initial position.

5. In a time-setting device for fuses, a fuse-firing unit having means which is moved through a variable angle to a fuse firing position, driving means including a frictional clutch having driving and driven elements for driving said means through the variable angle to the fuse firing position, and cooperating stop means on said driving and driven elements of said frictional clutch which is effective when said device is set for operation to limit the setting of said first named means whereby the driving means may be moved to a predetermined safety position and thereafter a predetermined time must elapse before said first-named means can be moved to the fuse firing position.

6. Apparatus as described in claim 5 wherein said driving and driven elements are in the form of two disc means held in frictional engagement and the means cooperating therewith is in the form of a peripheral nose on one of said discs and a pair of axially extending pins upon the other said discs.

7. Apparatus as described in claim 5 wherein said driving means is a clockwork having a main spring which is completely wound thereby to move the stop means to said safety position.

ADOLF WEISZ.
